Hyman Berman, Attorneys

UNITED STATES PATENT OFFICE

2,099,832

PUMP HANDLE STRUCTURE

Valley A. Thomas, Manila, Ark.

Application July 10, 1936, Serial No. 89,975

3 Claims. (Cl. 103—215)

My invention relates generally to operating handle structure for manually operating pumps, and an important object of the invention is to provide a more easily operated, more durable, and 5 more efficient arrangement of this character.

Other important objects of my invention will be apparent from a reading of the following description taken in connection with the drawing, wherein for purposes of illustration I have shown 10 a preferred embodiment of my invention.

In the drawing:—

Figure 1 is a general side elevational view of an embodiment of the invention showing the same applied to a pump.

15 Figure 2 is a longitudinal sectional view taken through Figure 1 approximately on the line 2—2.

Figure 3 is a transverse vertical sectional view taken through Figure 2.

Figure 4 is a longitudinal sectional view.

20 Figure 5 is a transverse vertical sectional view taken through Figure 1 approximately on the line 5—5 and looking toward the right in the direction of the arrows.

Figure 6 is an elevational view of one end of 25 the front handle per se.

Referring in detail to the drawing, the numeral 5 generally designates a conventional type of pump casing in which works a suction piston 6 which is mounted on a cage 7 which has adjustably connected thereto by means generally designated 8, the lower end of the pump rod 9 whose upper end is bifurcated to provide the furcations 10 and 11 which journal a fork or pin 12 on which is arranged and clamped between the furcations 11 and 12 the disk body 13 which includes a race on its periphery holding the ball bearings 14 and a rotatable annulus 15 provided on its radially inward face with a race confining the ball bearings 14.

40 Clamped around the periphery of the annulus 15 are the arms 17 and 18 of the pump handle per se which is generally designated 19 and which is tubular in form and assumes the general outline shown in Figure 1.

45 At the fulcrum point of the handle 19 an opening 20 is provided in the bottom of the tubular handle as shown in Figures 2 and 3 and mounted in place therein is a ball bearing structure which is generally designated 21 and which includes the annulus 22 fastened to the handle and the body 23 which is held to the annulus 22 by the ball bearings 24. The disk or body 23 has an axial opening 25 which receives a pin 26 on the pump casing bracket 27 whereby the handle 19 is fulcrumed on the pump casing. As shown in Fig-

ure 2 the bearing structure just described projects from the bottom of the handle 19 through the opening 20.

The foregoing manner of connecting the ball bearing structures with the inner end and with the fulcrum point of the handle and the tubular formation of the handle, made it possible to construct the arrangements of the invention cheaply and efficiently, and produce mechanically superior arrangements. It is obvious that the use 10 of ball bearings in the particular manner set forth lengthens the life of the pump structure, renders the same more nearly noiseless, and facilitates operation of the handle for pumping purposes.

15 Although I have shown and described herein a preferred embodiment of my invention, it is to be definitely understood that I do not desire to limit the application of the invention thereto, and any change or changes may be made in the 20 materials, and in the structure and arrangement of the parts, within the spirit of the invention and the scope of the subjoined claims.

What is claimed is:—

1. In combination, a support, a hollow pump 25 handle, a ball bearing including an outer race mounted in an opening formed in the underside of said pump handle intermediate its ends, said ball bearing further comprising an inner race and balls disposed between the inner and outer races, said bearing having a portion depending below said pump handle, a pivot on said support supportably traversing said inner race and mounting said pump handle on said support.

2. In combination, a support, a hollow pump 30 handle pivoted intermediate its ends on said support, a dependent pump plunger, a ball bearing composed of an outer race, an inner race, and balls disposed between the inner and outer races, one end of said hollow pump handle being 35 formed with opening means receiving and securing said outer race, means on said pump handle embracing and fastening said outer race in place, and a transverse element on the upper end of said dependent pump plunger traversing said inner race and operatively connecting said pump plunger to said pump handle.

3. In combination a support, a hollow pump 40 handle and a dependent pump plunger, said hollow pump handle being formed in its bottom with a first opening intermediate its ends, and with a second opening at the pump plunger end, a first ball bearing mounted in said first opening and comprising a stationary outer race fastened in 45 said first opening, a relatively rotatable inner 50 race fastened in said second opening, and a ball bearing 55 mounted in said second opening.

- race, and balls disposed between and connecting the outer and inner races, means operatively connecting said inner race and said support; and a second ball bearing mounted in said second opening and comprising a stationary outer race fastened in said second opening, a relatively rotat-

able inner race, and balls disposed between and connecting the outer and inner races, and means operatively connecting the inner race of said second ball bearing to the upper end of said pump plunger.

VALLEY A. THOMAS.
